Attorney.

UNITED STATES PATENT OFFICE.

WILLIAM H. SAMO, OF NEW YORK, N. Y.

TOILET SEAT.

Application filed July 14, 1920. Serial No. 396,172.

To all whom it may concern:

Be it known that I, WILLIAM H. SAMO, a citizen of the United States of America, residing at New York, in the county of 5 New York and State of New York, have invented new and useful Improvements in Toilet Seats, of which the following is a specification.

The object of the invention is to provide 10 a simple and relatively inexpensive hinged mounting for a toilet seat and lid under conditions providing for the independent movement thereof and without involving the use of more or less expensive castings such 15 as are necessary in the double hinged construction ordinarily employed in this connection; and with this object in view, the invention consists in a construction and combination of parts, of which a preferred 20 embodiment is shown in the accompanying drawings, wherein:—

Figure 1, is a plan view of a closet seat and lid with the mounting embodying the invention.

Figure 2, is a detail enlarged sectional view of the hinge mounting on the plane indicated by the line 2—2 of Figure 1, showing the seat and lid members in full lines in the normal or closed, and in the 30 dotted lines in the raised or inoperative positions.

Figure 3, is a detail in perspective of the hinge bar or member.

Figure 4, is a similar view of the hinge 35 member of the lid.

Figure 5, is a similar view of the hinge member of the seat.

The mounting embodies essentially a hinge bar or member 10 shown in detail in 40 Figure 3, consisting in the construction illustrated of parallel bars 10^a and 10^b which may be formed of hard wood or any equivalent relatively inexpensive material secured together for example, by bolts 11 45 which may extend through the flange 12 of the bowl 13 to secure the hinge bar in place upon the bowl at the rear side thereof as in the ordinary practice, in combination with hinge members carried respectively by 50 the lid 14 and seat 15 which are pivotally connected with a hinge bar for swinging movement in a vertical plane and adapted to be arranged in parallelism and contact, when closed as indicated in full lines in Fig-

ure 2. The upper element 10^a of the hinge bar is provided with tongues 16 and intervening recesses 17, and the hinge member of the lid is provided with tongues 18 and interposed recesses 19 so that the tongues of the lid are adapted to be arranged in intercurrent interlocking relation with the tongues of the upper element of said bar for engagement by a main pintle 20. The lower element of the hinge bar is correspondingly provided with tongues 21 separated by recesses 22 while the seat 15 is provided with tongues 23 and intermediate recesses 24 so that the tongues of the said seat may be disposed in intercurrent interlocking relation with the tongues of the lower element of the bar and in a plane parallel with the intercurrent interlocking tongues of the lid and upper element of the bar for engagement by a common pintle 25 disposed parallel with the pintle 20 and 75 in a different vertical plane therefrom, or in other words, in advance of the vertical plane of the pintle 20 so that when elevated as shown in dotted lines in Figure 2, the lid and seat occupy substantially parallel 80 upright planes with a sufficient rearward inclination to hold them in their adjusted positions.

The tongues of the upper and lower elements of the hinge bar are arranged in 85 staggered relation, the tongues 16 of the upper element being disposed in vertical plane with the recesses 22 of the lower element, while the tongues 21 of the lower element are disposed in the vertical planes 90 of the recesses 17 to the end that there is a break joint relation between the hinge members of the lid and seat to insure an air-tight closure of the bowl when the seat and lid are in their closed or lowered position.

The arrangement described provides for compactness of the structure and the presentation of a substantially unbroken surface in either the closed or open position 100 of the parts or with the lid in an elevated and the seat in its normal or horizontal position. Obviously the pintles are the only portions of the mounting which are subjected to any noticeable wear in the operation of the device, and being of simple construction adapted to be threaded into place from one end or the other of the 105

hinge bar may be readily replaced when necessary to restore the mounting to its original condition.

The invention having been described, 5 what is claimed as new and useful is:—

1. A hinge mounting for toilet bowls having a hinge bar and lid and seat members connected therewith, said hinge bar having parallel upper and lower series of 10 tongues, said lid and seat members also having each a series of tongues arranged respectively in intercurrent relation with the tongues of the upper and lower series of the hinge bar, and pintles engaging respectively 15 said intercurrent tongues, the tongues of the upper series being arranged in staggered relation with those of the lower series.

2. A hinge mounting for toilet bowls having a hinge bar and lid and seat members connected therewith, said hinge bar 20 having parallel upper and lower series of tongues, said lid and seat members also having each a series of tongues arranged respectively in intercurrent relation with the tongues of the upper and lower series 25 of the hinge bar, and pintles engaging respectively said intercurrent tongues, the tongues of the upper series being arranged in staggered relation with those of the lower series, the pintle of the upper series of 30 tongues being disposed in a parallel plane in rear of that of the lower series.

In testimony whereof I affix my signature.

WILLIAM H. SAMO.
